ADJUSTABLE EVACUATOR

William C. Groeniger, Columbus, Ohio, assignor
to John B. Pierce Foundation, New York, N. Y.,
a corporation of New York

Application April 4, 1935, Serial No. 14,578

7 Claims. (Cl. 4—69)

My present invention relates to adjustable evacuators.

Embodiments of my present invention, designated adjustable evacuators, possess characteristics of the general nature of half-syphon legs, that is to say, function to form the posterior leg of a syphon, the anterior leg of which is constituted of an upwardly extending passage with which my evacuator is connected and serving therewith to discharge a defecator, the evacuator being constructed for adjustment to accommodate varying relative positions of its connection with the anterior leg of the syphon and the connection of the evacuator to the soil pipe or other channel of discharge.

My present invention is a development of my evacuator set forth and claimed in my copending application Serial #4,620, filed February 2nd, 1935, and entitled Evacuators.

The general characteristics of my present invention reside in an uppermost portion arranged to have its inflow opening detachably connected to the uppermost portion, i. e. discharge of an upwardly extending leg of a lateral outlet type of defecator or to the uppermost portion, i. e. discharge of an upwardly extending anterior syphon leg of a non-lateral outlet type of defecator; such uppermost portion includes a weir serving per se as or in conjunction with a wall of the uppermost portion of the anterior syphon passage or leg as a dam. The evacuator further includes a bulge or elbow formation at an upper portion thereof, whereby upon flow of the effluent discharged from the defecator, a portion of the quantity of air originally in the bulge or elbow formation, is entrained thereby giving rise to sub-atmospheric pressure of the retained air. My evacuator further includes a downwardly extending central or other intermediate portion, the effective cross-sectional area of which is less than that of the uppermost portion of the evacuator, thus providing for a relatively restricted cross-sectional mass of the effluent through such intermediate portion. Pursuant to my present invention, the defecator further includes an adjustable component part, advantageously an adjustable foot or lowermost portion to afford communication of the discharge opening of the evacuator relative to its inflow opening, thereby in turn affording a range of positional relationship between the defecator or other device with which my evacuator is connected at its inflow end and the soil pipe or other channel of discharge with which my defecator is connected for the eventual discharge of the effluent conducted therethrough.

Further features and objects of the invention will be more fully understood from the following detail description and the accompanying drawing, in which

Fig. 1 is a vertical central sectional view of a preferred embodiment of my invention, illustrating the principle of my invention as applied to an adjustable foot serving as the adjustable component part of my evacuator.

Fig. 2 is an elevational view of Fig. 1.

Fig. 3 is a vertical central sectional view of another embodiment of my invention.

Fig. 4 is an elevational view of Fig. 3.

Referring to the preferred embodiment of my invention shown in Figs. 1 and 2, the evacuator 15 comprises an uppermost portion 11, preferably provided with an enlarged and thickened annular wall encircling its inflow opening 12. Such thickened wall portion 11 has particular application for its connection with the discharge opening 20 of the upwardly extending syphon leg of a lateral outlet type of defecator, such as is shown in my copending application Serial #749,069, filed October 19th, 1934, entitled Defecator. For other types or embodiments of defecators, such wall 25 construction as indicated at 11 is suitably arranged, as is understood by those skilled in the art.

In the particular evacuator shown in Figs. 1 and 2, the central and downwardly extending portion 13 has an effective diameter definitely less than that of its inflow opening 12 and the portion intermediate the stated component portions includes the elbow portion, see its wall 14 and therewith combined weir or dam 15. The interior of 30 the elbow portion 14 is designed to have a predetermined volume in correspondence with the characteristics of the inflow opening 12 and the downwardly extending relatively restricted portion 13, whereby upon discharge of the effluent 35 through the inflow opening 12, effective removal of the air takes place progressively from the interior of such elbow portion to thereby reduce the pressure of such air retained therein, for the purpose of maintaining sufficient vacuum for initiating and maintaining syphonic action during the 40 stage of discharge of a defecator or the like.

Advantageously, the inner face, see 12a, of the lower portion of the wall 12 extends substantially horizontally and in substantial alignment with 50 the lower wall of the discharge opening of the upwardly extending lug of a lateral outlet defecator or of the anterior syphon passage or leg, the discharge of the defecator or the like including a gradual rising of the effluent above such dam or 55

weir until the effluent at the stage of full discharge substantially fills the whole of the inflow opening 12. The provision of the relatively restricted downwardly extending portion 13 serves to advance in time period the complete filling of the effluent at and beyond the inflow opening 12 of the evacuator, thus speeding up the formation of full syphonic action accompanied by the speeding up of the condition of sub-atmospheric pressure of 10 the air retained within the interior of the elbow portion 14.

The lower component portion of my evacuator possesses the general characteristics of maintenance of such full syphonic action, including the 15 preservation of the sub-atmospheric pressure within the upper portions of the evacuator, had advantageously by the formation of a curtain or wall of the effluent effected by the flow of the effluent through the central portion 13 in contact with 20 and downwardly below the projection 16, illustrated in the embodiment shown in Figs. 1 and 2 as a component part of the adjustable foot or lowermost portion 17 of the defecator.

I also prefer to dish, i. e. lowerly hollow-out the 25 bottom portion, see 17a, of the foot portion 17, which in cooperation with the discharge outlet 18 serves to create a pool of the effluent having a general level indicated by the dot and dash line 17b, during the stage of discharge of the effluent 30 through the defecator; it will be apparent, however, that such pool will not be quiescent during the stage of the effluent, at which time the curtain of the effluent, as above set forth, creating such pool, causes surges of the pool.

35 The extent of the dishing of the bottom 17a of the foot portion 17, and the relative location of the surface 18a of the lowermost portion of the wall of the discharge opening 18 may be varied as desired.

40 The adjustability of the foot portion 17 of my defecator, as illustrated in Figs. 1 and 2, is advantageously had by a telescope connection with the lower end of the central portion 13 of the defecator, as by means of the upwardly extending 45 annular flanged wall 19, desirably including an inwardly extending shoulder, see 19a, for the seating of the lowermost edge, see 13a, of the central portion 13 of the defecator within such annular flange 19, such telescope relationship 50 affording rotary articulation includes vertically adjusted telescoped positioning of the foot portion 17, relative to the upper portion of my defecator, and conversely rotary articulation of the upper portion of my defecator relative to its foot portion 55 17.

As is shown in Fig. 2, the stated face 18a of the wall of the discharge opening 18 of the foot portion 17, is preferably flattened and disposed in a substantially horizontal plane.

60 The embodiment of my invention shown in Figs. 3 and 4 conforms largely to that illustrated in Figs. 1 and 2, and like parts are designated by like reference characters. The embodiment shown in Figs. 3 and 4 illustrates in particular 65 a projection 16a corresponding in general to the projection 16 of the embodiment shown in Figs. 1 and 2, but extending, advantageously arcuately, toward the central longitudinal axis of the defecator, whereby to more effectually form the curtain of the effluent, that is to say, to advance in 70 time the instant of formation of the curtain, condense the curtain in physical formation during the stage of full discharge and prolong the period of its formation, thereby more effectively precluding the entry of air through the discharge open-

ing 18 of the evacuator in a direction counter to that of the flow of the effluent, and in turn enhancing the discharge of the defecator or other receptacle with which my evacuator is connected.

Coacting with such inwardly directed projection 5 16a, the oppositely disposed wall portion, see 16a, of the leg 17 may be contoured in direction and facial formation corresponding to the projection 16a.

It will be understood that the configuration of 10 the body and other component parts of my evacuator may be varied, such as Z, S or like configuration illustrated in my aforesaid copending application Serial #4,620, combined with an adjustable foot portion or other adjustable component 15 part, for importing articulation to my evacuator for adjustable relationship between its inflow opening and its discharge opening.

A suitable sealing medium is applied in the 20 joint of the relatively articulated portions, where- 25 by upon final positioning of the evacuator, i. e., upon completion of its connections at its respective inflow opening and its discharge opening, its joint of articulation including adjusted vertical positioning is sealed against escape of sewer and 30 other unsanitary gases, and also to preclude the entry of air therethrough in possible diminution of the syphonic action.

Whereas I have described my invention by reference to specific forms thereof it will be understood 35 that many changes and modifications may be made without departing from the spirit of the invention.

I claim:

1. As an article of manufacture, a posterior 35 syphon half-leg provided with intake and outtake openings, comprising an upper section communicating directly with the intake opening and extending wholly horizontally therefrom, an upper elbow section communicating directly with said upper horizontally extending section, said elbow section being of relatively large cross-sectional area, said article further comprising a lower downwardly extending section of relatively lesser cross-sectional area, said article further including a 45 lowermost section arranged for adjusted positioning relative to said lower downwardly extending section, the walls of said article being imperforate between its intake and outtake openings.

2. As an article of manufacture, a posterior 50 syphon half-leg provided with intake and outtake openings, comprising an upper section communicating directly with the intake opening and extending wholly horizontally therefrom, an upper elbow section communicating directly with said upper horizontally extending section, said elbow section being of relatively large cross-sectional area, said article further comprising a lower 55 downwardly extending section of relatively lesser cross-sectional area, said article further including a lowermost section arranged for adjusted horizontal positioning relative to said lower downwardly extending section, the walls of said article being imperforate between its intake and outtake openings.

3. As an article of manufacture, a posterior 60 syphon half-leg provided with intake and outtake openings, comprising an upper section communicating directly with the intake opening and extending wholly horizontally therefrom, an upper elbow section communicating directly with said upper horizontally extending section, said elbow section being of relatively large cross-sectional area, said article further comprising a lower 65 downwardly extending section of relatively lesser cross-sectional area, said article further including a lowermost section arranged for adjusted horizontal 70 positioning relative to said lower downwardly extending section, the walls of said article being imperforate between its intake and outtake openings.

cross-sectional area, said article further including a lowermost section arranged for adjusted vertical positioning relative to said lower downwardly extending section, the walls of said article being imperforate between its intake and outtake openings.

4. As an article of manufacture, a posterior syphon half-leg provided with intake and outtake openings, comprising an upper section communicating directly with the intake opening and extending wholly horizontally therefrom, an upper elbow section communicating directly with said upper horizontally extending section, said elbow section being of relatively large cross-sectional area, said article further comprising a lower downwardly extending section of relatively lesser cross-sectional area, said article further including a lowermost section arranged for adjusted horizontal and vertical positioning relative to said lower downwardly extending section, the walls of said article being imperforate between its intake and outtake openings.

5. As an article of manufacture, a posterior syphon half-leg provided with intake and outtake openings, comprising an upper section communicating directly with the intake opening and extending wholly horizontally therefrom, an upper elbow section communicating directly with said upper horizontally extending section, said elbow section being of relatively large cross-sectional area, said article further comprising a lower downwardly extending section of relatively lesser cross-sectional area, said article further comprising a horizontally adjusted lowermost section extending horizontally, said lowermost section having a dish-like lower wall formation, the walls of

said article being imperforate between its intake and outtake openings.

6. As an article of manufacture, a posterior syphon half-leg provided with intake and outtake openings, comprising an upper section communicating directly with the intake opening and extending wholly horizontally therefrom, an upper elbow section communicating directly with said upper horizontally extending section, said elbow section being of relatively large cross-sectional area, said article further comprising a lower downwardly extending section of relatively lesser cross-sectional area, said article further comprising a vertically adjusted lowermost section extending horizontally, said lowermost section having a dish-like lower wall formation, the walls of said article being imperforate between its intake and outtake openings.

7. As an article of manufacture, a posterior syphon half-leg provided with intake and outtake openings, comprising an upper section communicating directly with the intake opening and extending wholly horizontally therefrom, an upper elbow section communicating directly with said upper horizontally extending section, said elbow section being of relatively large cross-sectional area, said article further comprising a lower downwardly extending section of relatively lesser cross-sectional area, said article further comprising a horizontally and vertically adjusted lowermost section extending horizontally, said lowermost section having a dish-like lower wall formation, the walls of said article being imperforate between its intake and outtake openings.
